Patented May 16, 1961

190,333

GOLFER'S TOOL

Arthur M. Gunderson, 4117 Wayzata Blvd.,
Minneapolis, Minn.

Filed Oct. 10, 1960, Ser. No. 62,433

Term of patent 14 years

(Cl. D9—2)

Fig. 1 is a perspective view of the golfer's tool, showing my new design;

Fig. 2 is a top plan view;

Fig. 3 is a bottom plan view;

Fig. 4 is a front elevation view;

Fig. 5 is a rear elevation view;

Fig. 6 is an elevation view at one end of the tool, and

Fig. 7 is an elevation view at the other end of the tool.

I claim:

The ornamental design for a golfer's tool, as shown.
